Primary Examiner—Philip S. Hyder**Attorney, Agent, or Firm—Townsend and Townsend and Crew****[57] CLAIM**

The ornamental design for a computer carrying case, as shown and described.

DESCRIPTION

FIG. 1 is a perspective view of a computer carrying case, showing our new design;

FIG. 2 is a top plan view thereof;

FIG. 3 is a front elevational view thereof;

FIG. 4 is a right side elevational view, the left side elevational view being a mirror image;

FIG. 5 is a rear elevational view thereof;

FIG. 6 is a bottom plan view thereof; and,

FIG. 7 is a perspective view of the computer carrying case in the open position.

The broken line showing of the shoulder strap is for illustrative purposes only and forms no part of the claimed design.
